EUGENE H. SOUTER, OF INDEPENDENCE, MISSOURI, ASSIGNOR TO THE CAR-RECORD COMPANY, OF KANSAS CITY, MISSOURI, A CORPORATION

RECORD-CARRYING DEVICE FOR AUTOMOBILES

Application filed June 27, 1929. Serial No. 374,233.

My invention relates to record carrying devices for automobiles, and the object of the invention is to provide a simple and inexpensive record carrying device for automobiles having facilities for demountably applying the same to the instrument board of the automobile and for slidably carrying a plate adapted to bear record data respecting the lubrication of the operating parts of the automobile.

I attain these objects and other advantages by means of the device illustrated in the accompanying drawing in which—

Figure 1 is a portion of the instrument board of an automobile, and showing my invention applied thereto in operative position.

Figure 2 is a perspective view of the device embodying my invention apart from the automobile.

Figure 3 is a plan view of the lower side of the device, and showing the means for carrying the recording plate, a part of the invention.

Figure 4 is a sectional view of the instrument board, and showing my invention applied thereto, on the line 4—4 on Figure 1.

Figure 5 is a plan view of the recording plate, and

Figure 6 is a sectional view of the frame portion of the device on line 6—6 in Figure 2.

Similar reference numerals refer to corresponding parts throughout the several views.

Referring to the drawings, the numeral 1 designates a portion of the instrument board of an automobile and 2 a portion of the windshield of the same. 3 designates a record carrying device constructed in accordance with my invention and preferably formed of a sheet of suitable metal of a thickness to be readily blanked and formed to shape. The device comprises an elongated body portion 4 which terminates at one end in a transverse frame portion 5 disposed at right angles to the body portion and in which frame portion advertising matter may be displayed, as shown at 6 in Figure 1. The body has side portions 7 which are partly formed inwardly at right angles to the side portions to form

slide bearings 8. One slide bearing 8 is cut away longitudinally to form a finger 9 which may be bent at its free end portion to effect slight friction on the recording plate herein-after described when the same is disposed in operative position on the slide bearings 8. A lug 10 is formed up of the upper side of the body portion and an angularly disposed head portion 11 is arranged at the upper end of the lug and provided with internal screw threads to receive the screw threads on a supporting and adjusting rod 12 operating through the head. A nut 13 is mounted on the forward portion of the rod and adapted to press against the adjacent end of the head 11 to hold the relative adjustment of the rod with respect to the angle 14 on the inner side of the instrument board to thereby hold the device secured on the same. An elongated plate 15 having its upper face divided longitudinally and transversely by lines 16 into sections 17 is slidably carried by the device on the slide bearings 8. A record of the lubrication of the operating parts of the automobile may be entered in the sections 17 for future reference.

The device is applied to the instrument board of the automobile by placing the same under the angle portion of the board and moving it inwardly until the frame portion 5 is in close relation to the front side of the board. Then the screw 12 is run forwardly until the point of the screw contacts with the inside corner of the angle of the instrument board, sufficient pressure being applied to the screw to draw the frame portion 5 against the front face of the instrument board thereby holding the body of the device in close relation to the under side of the angle portion 18 and thus securing the device in place. The nut 13 is then run to bear on the forward end of the head 11 to hold the adjustment effected by the screw. The plate 15 is then slidably inserted in the device upon the bearings 8 whereupon the friction exerted by the finger 9 will hold the plate in place.

When the motor and other parts of the automobile are serviced the date of the service is entered on the recording plate 15, together with the speedometer reading at the

100

time and the particular part or parts of the automobile then receiving attention, checking the proper section 19, as is shown in Figure 5. In the frame portion 5 may be carried a transparent panel 20, an advertising plate 21, and a back supporting plate 22 to hold the parts in the frame, as shown in Figure 6. The panel 20 and plate 21 may be held in place by a sheet of adhesive paper or cloth affixed to the plate 22 and the frame in the well known manner.

The device has great utility and makes possible the combination of advertising and merchandising. It is a convenient means of keeping accurate data of record which is always within the reach of the operator and by which it may be readily ascertained if the operating parts of the automobile should be serviced. Moreover, the device conceals the recording plate and keeps the record thereon perfectly clean and legible. The recording plate is pulled outwardly when entries are to be made and pushed inwardly thereafter.

Having described my invention what I claim is—

1. A record carrying device for automobiles comprising a flat elongated case having edge portions terminating in flanges projecting inwardly of the case and adapted to support thereon a writing plate and an upwardly extending transverse frame portion at one end and adapted to bear upon the front side of the instrument board, an upwardly extending lug mounted on the upper side of the case and having an obliquely disposed screw threaded head portion, and a supporting and adjusting screw rod operably mounted in the oblique head on said lug, and adapted to engage the inner side of the angle portion of an automobile instrument board to supportingly adjust the case on the same.

2. The combination, in a record carrying device for automobiles, of a flat elongated case having edge portions terminating in flanges projecting inwardly of the case and adapted to support thereon a writing plate and an upwardly extending portion at its forward end and forming with the body of the case an angle adapted to register with the angle portion of the lower edge of an automobile instrument board, and a screw rod mounted on the upper side of the case at an oblique angle to engage the inner corner of the angle portion of the instrument board to supportingly adjust the case in close relation to the angle of the lower portion of the instrument board.

3. A record carrying device for automobiles comprising a sheet metal blank bent into shape to provide a flat elongated holder section having edge portions terminating in flanges projecting inwardly of the holder section and adapted to support thereon a writing plate and bent upwardly at one end of the holder section to form an angle adapted

to register with the angle of the lower portion of an automobile instrument board, there being an opening in the bent up section adapted to display therein publicity matter, an upwardly extending lug formed on the upper side of the holder section and provided with an obliquely disposed hollow screw threaded head portion, a screw threaded rod operably mounted in the head on said lug and adapted to engage the inner corner of the angle of the lower portion of the instrument board to support the device thereon in operative position and to force the device into close relation with the angle portion of the lower edge of the instrument board.
